(57) **CLAIM**

The ornamental design for a toilet seat and cover combination, as shown and described.

DESCRIPTION

FIG. 1 is a front perspective view of a toilet seat and cover combination showing our new design;

FIG. 2 is a rear perspective view thereof;

FIG. 3 is a top plan view thereof;

FIG. 4 is a side elevational view thereof, the opposite side view being a mirror image of that shown;

FIG. 5 is a front elevational view thereof;

FIG. 6 is a rear elevational view thereof;

FIG. 7 is a front perspective view of the seat portion with the cover removed for ease of illustration;

FIG. 8 is a cross-sectional view of the cover taken along line 8—8 in FIG. 3; and,

FIG. 9 is a cross-sectional view of the cover taken along line 9—9 in FIG. 3.

The portions of the seat and cover not shown and the portions shown in dotted lines are not part of the claimed design.
